UNITED STATES PATENT OFFICE.

JAMES M. EDWARDS, OF WAUPACA, WISCONSIN, ASSIGNOR OF FIFTY PER CENT TO
JOSEPH J. BURKE AND SAMUEL J. BURKE, BOTH OF DUBUQUE, IOWA.

GLOVE.

Application filed October 19, 1927. Serial No. 227,328.

This invention relates to apparel and more particularly to a hand covering which may be either a glove or a mitten and is partially covered with rubber so that the glove will 5 be prevented from becoming soaked with water during wet weather or when handling wet objects.

One object of the invention is to provide a glove having rubber applied thereto in 10 such a manner that it may prevent the glove from becoming soaked with water when handling wet objects such as large stones or wet posts but at the same time leaves the back of the glove uncovered with rubber so 15 that the hands will be prevented from perspiring and becoming chilled during cold weather.

Another object of the invention is to cover the seams with rubber so that they will be 20 protected and the glove prevented from ripping due to the stitches rotting or becoming worn.

Another object of the invention is to so 25 apply the rubber to the glove that the sides of the body portion and finger stalls and the sides of the wristlet will be prevented from becoming soaked with water but at the same time allow the wristlet to contract tightly about the wrist of the person wearing the glove.

Another object of the invention is to gradually reduce the thickness of the rubber 30 coating between the finger stalls and thereby allow these portions of the glove to be protected but at the same time prevent the glove from being uncomfortable when worn.

The invention is illustrated in the accompanying drawings, wherein

Figure 1 is a view looking at the back of 40 the improved glove.

Figure 2 is a transverse sectional view through the glove, taken on the line 2—2 of Figure 1.

Figure 3 is an enlarged transverse sectional view through one of the finger stalls, taken 45 on the line 3—3 of Figure 1.

The improved hand covering constituting the subject matter of this invention has been 50 illustrated as a glove although it could be incorporated in a mitten. The glove consists of a body portion 1 which is preferably formed of woven fabric in the usual manner and includes a thumb stall 2 and finger stalls 3. The wristlet 4 which is carried by 55 the body 1 is formed of knitted fabric hav-

ing longitudinally extending ribs, as clearly shown in Figure 1, so that the wristlet may be temporarily expanded when putting on a glove and then contract about the wrist of the wearer so that it fits close to the wrist 60 and prevents cold air from entering the glove.

At the present time gloves are in use which are entirely coated with rubber in order to render them waterproof but it has 65 been found that when the entire glove is coated with rubber, ventilation is cut off and this causes the hands to perspire and in cold weather the hands quickly become chilled. In order to render my glove waterproof and, 70 at the same time permit ventilation which will prevent the hands from perspiring, I employ a coating 5 of rubber which covers the entire front of the glove and the ends of the thumb and finger stalls and also extends 75 along the sides of the stalls and along the sides of the body portion of the glove and wristlet. By having the rubber coating extend between the stalls, as shown at 6 in Figure 1, and along the sides of the stalls, 80 articles may be grasped in the usual manner and there will be no danger of the sides of the stalls and the portions of the gloves between the stalls becoming wet. It should also be noted that the portions 7 of the 85 rubber covering which extend along the sides of the stalls are gradually reduced in thickness as clearly shown in Figure 3. By referring to this figure it will be seen that the rubber coating for a finger stall is sub- 90 stantially crescent shaped in cross section. Therefore, while the rubber applied to the front of the stall will be sufficiently thick to give long wear to a glove, it will not be bulky between the stalls and the gloves can 95 be comfortably worn and will not be clumsy. The portions 8 of the rubber covering which are applied to the side portions of the body of the glove and wristlet are also reduced in thickness toward their marginal edges, as 100 shown in Figure 2, and these portions 8 increase in width and overlap the back of the glove to a greater extent from the thumb and little finger stall toward the rear end of the glove. By this arrangement the sides 105 of the body portion of the glove and the sides of the wristlet will be well protected and large stones or logs or posts may be easily lifted without the wristlet and the side portions of the glove becoming wet. It 110

will thus be seen that the entire portion of the glove which is liable to come in contact with articles being handled will be prevented from becoming soaked upon contact 5 with wet articles but the rear portion of the glove and the thumb and finger stalls will be left uncovered and thereby allow ventilation which will prevent the hand from perspiring. It will also be noted that this permits 10 the uncovered rear portion of the wristlet to expand and contract and therefore the glove may have a close fit about the wrist of the wearer and cold air cannot enter the glove about the wrist. It should be further noted that since the seams are 15 covered by rubber the stitches will be prevented from becoming worn or rotted. Therefore, the gloves will not quickly rip along the seams and will last longer.

20 Having thus described the invention, what I claim is:

1. A hand covering comprising a body of woven fabric, a wristlet of knitted fabric carried by said body, and a facing of rubber applied to the front face of the body and 25 wristlet and overlying the sides and back faces thereof without extending entirely across the back faces whereby the wristlet may contract tightly about the wrist of a 30 wearer and ventilation of the hand covering be permitted when worn.

2. A hand covering comprising a body of porous and relatively non-stretchable material, a wristlet of stretchable material carried by said body and adapted to contract 35 about the wrist of a person wearing the hand covering, and a facing of waterproof material applied to the front faces of the body and wristlet with portions covering the

sides thereof and overlying their back faces 40 but not entirely covering the latter.

3. A hand covering comprising a porous body having thumb and finger stalls, a wristlet of knitted fabric carried by said body and adapted to contract tightly about the 45 wrist of a person wearing the hand covering, and a facing of waterproof material covering the front faces of the body and wristlet with portions extending between the stalls, said facing covering the sides of the 50 wristlet, body and stalls and overlying the back faces thereof without entirely covering the latter whereby a hand may be kept warm without perspiring.

4. A hand covering comprising a porous 55 body having thumb and finger stalls, a wristlet of knitted fabric carried by said body and adapted to contract tightly about the wrist of a person wearing the hand covering, and a facing of waterproof material 60 covering the front faces of the body and wristlet with portions extending between the stalls, said facing covering the sides of the wristlet, body and stalls and overlying the 65 back faces thereof without entirely covering the latter, the extent to which the facing covers the back of the body and wristlet increasing from the stalls to the rear edge of the wristlet.

5. A hand covering comprising a fabric 70 body including an expandable and contractable wristlet, and a facing of waterproof material applied to the front faces of the body and wristlet with portions covering the sides 75 thereof and overlying their back faces without entirely covering the back faces.

In testimony whereof I affix my signature.
JAMES M. EDWARDS. [L. S.]
